UNITED STATES PATENT OFFICE.

ISAAC E. PALMER, OF MIDDLETOWN, CONNECTICUT, ASSIGNOR TO THE I. E. PALMER CO., OF MIDDLETOWN, CONNECTICUT, A CORPORATION OF CONNECTICUT.

COUCH-HAMMOCK AND BACK-REST THEREFOR.

1,103,907.

Specification of Letters Patent: Patented July 14, 1914.

Continuation in part of application Serial No. 721,765, filed September 23, 1912. This application filed December 30, 1912. Serial No. 739,234.

To all whom it may concern:

Be it known that I, ISAAC E. PALMER, a citizen of the United States, and a resident of Middletown, in the county of Middlesex and State of Connecticut, have invented an Improvement in Couch-Hammocks and Back-Rests Therefor, of which the following description, in connection with the accompanying drawings, is a specification, like characters on the drawings representing like parts.

This invention relates to couch hammocks and back rests therefor.

This application is a continuation of my application Serial No. 721,765, filed September 23, 1912, now Patent No. 1,053,860, dated February 18, 1918.

In order that the principle of the invention may be readily understood, I have disclosed a single embodiment thereof in the accompanying drawing, wherein—

Figure 1 is a front elevation of a couch hammock, having my invention applied thereto; Fig. 2 is a transverse sectional view thereof showing one suspension end in elevation; Fig. 3 is a side elevation of the connecting and supporting means for one end of the back rest showing the bars or rods in section; Fig. 4 is a front elevation thereof; and Fig. 5 is a view similar to Fig. 3, but reversed, of a different form of the invention.

Referring more particularly to the drawings, the frame or seat of the hammock is represented at 1. This frame is composed of longitudinal or side and transverse or end members, either metallic or wooden, connected together into preferably substantially rectangular form, detachably or otherwise. The frame is provided with any suitable seating, such, for example, as one formed of wire links or rope or cloth, and if desired end and side springs may be employed to connect the seating to the frame. I have herein indicated a cloth seating 1', over which may be positioned a mattress.

The hammock is provided with two upturned ends represented at 2—2 in Fig. 1. These ends may be of any suitable character, but are preferably composed of cloth, which may be individually connected to the hammock frame at its ends or if desired the hammock may be provided with a cloth body underlying or applied in suitable manner to the frame, and of which the upturned

ends form a continuation, as in the so-called Gloucester type of hammock. The said upturned or suspension ends are provided with spreaders 3—3 and with clew cords or hammock suspension means 3', 3', distributed at suitable transverse intervals therealong.

The hammock is provided with a suitable back or back rest which in this embodiment of the invention is represented as connected at its upper end or top to the upturned ends at a fixed height above the seating. Any other suitable connection at the upper end or top of the back rest may be provided to secure a fixed, but variable or adjustable relation with the suspension ends. I have herein represented the back as composed of one or more bars 4, three being herein shown. If desired, however, the back may be composed of cloth or other suitable material, or cloth and one or more rods or bars. I have herein represented the back as extending longitudinally of the hammock and as connected to both of the upturned ends.

In order to connect the back to the upturned ends, I have herein provided two wire brackets 5, one at each end of the hammock. Each of said brackets has a bent or hooked upper end 6 which takes over the spreader 3 and engages the same sufficiently tight to prevent displacement, the tip of the hook being preferably inturned as represented at 7 to prevent ready displacement of the bracket. By reference to Fig. 2, it will be observed that the hooked end 6 of each wire bracket 5 may engage one of the clew cords 3', so that the upper end of the back is held at a fixed point with respect to the suspension ends. However, the said brackets 5 may be adjusted transversely of the upturned ends by engaging the hooks 6 with the spreaders 3 adjacent any suitable clew cords 3'. Preferably, but not necessarily, the brackets 5 are connected to the upturned ends at a fixed height above the seat or frame 1. The engagement of the hooks 6 with the spreaders 3 is sufficiently loose to permit change in angularity of the back, as hereinafter described. Any other suitable connection between the upper portion of the back rest and the suspension ends may be provided, my invention being in no-wise limited in this respect.

In order to connect the rods or bars 4 to the brackets 5, I provide any suitable means,

such, for example, as two castings 8, one of which is adapted for connection to each bracket. Each of these castings is represented as provided with two ears 9—9 forming a partial bearing at one side of the bracket 5 and a coöperating ear 10 to form a partial bearing at the other side of the said bracket. Each ear 10 is represented as provided with a thumb nut 11 by means of 10 which the castings 8 may be secured at any desired height along the brackets 5, thus providing means securing the back at a fixed height above the seat. If desired, the said castings 8 may be permanently and immovably secured at a fixed height on the brackets 5. Each of the said castings 8 is provided with a plurality of sockets 12 corresponding in number to the bars 4, and to which the ends of said bars are connected by screw 13 20 entering holes in said sockets. Each of the brackets 5 is provided with a lower bent end 14 provided with a suitable pivotal opening 15 within which is received the headed end 16 of a rod or bar 17, the forward end of which is downwardly bent as indicated at 18. It will be understood that a rod or bar 17 is provided for the lower end of each of the brackets 5. Each of the 25 transverse or end members of the frame or seat is provided with a series of sockets 19 between the end of the mattress and the suspension or upturned end 2, with any one of which the downturned end 18 of the bracket may be securely engaged by being inserted 30 therein. In this manner, the angularity of the back may be varied. The hooked end 6 of each bracket 5 constitutes a pivotal point or fulcrum about which the back rocks when varying the angularity thereof by means of 35 the rods or bars 17. The rods or bars 17 constitute means independent of the upturned ends and coöperating with the back below the connecting means to vary the angularity of the back.

In Fig. 5, I have shown another form of the invention. Therein the bracket 20 is curved as shown and is provided with a lower bent end 21 adapted to enter any one of the openings 22 in the frame, thereby to 40 adjust the angularity of the back. In said Fig. 5, I have shown but one of the brackets 20, the other being similarly constructed. I have here represented two rods or bars 23.

I have herein illustrated certain forms of 45 means for engaging the seat and back rest below the upper terminal connecting means, to vary the angularity of the back rest. Instead of the means illustrated, I may employ any other means independent of the suspension ends and engaging the seat and back rest below the terminal connecting means to 50 vary the angularity of the back rest.

Having thus described one illustrative embodiment of my invention, I desire it to be understood that although specific terms 65 are employed, they are used in a generic and descriptive sense and not for purposes of limitation, the scope of the invention being set forth in the following claims.

Claims.

1. A couch hammock comprising a seat and two suspension ends, a back rest extending longitudinally of the hammock and provided with terminal connecting means adapted to engage said suspension ends and 70 to hold the upper edge of said back rest in substantially fixed relation with said ends, and other means independent of said suspension ends and engaging the seat and back rest below said terminal connecting 75 means to vary the angularity of said back rest.

2. A couch hammock comprising a seat, two upturned ends, hammock suspension means connected therewith, a back rest bar, 85 a flexible back rest depending therefrom, end brackets having fixed fulcrum points at their upper ends, coöperating with the upturned ends, hooks pivotally connected to the lower ends of said brackets, and means 90 independent of said upturned ends and coöperating with said hooks, for supporting the lower end of said back rest either in a vertical or in an inclined plane.

3. A couch hammock comprising a seat 95 provided with a frame, two upturned ends, hammock suspension means connected therewith, a back rest bar, a flexible back rest depending therefrom, end brackets having fixed fulcrum points at their upper ends, 100 coöperating with the upturned ends, hooks pivotally connected to the lower ends of said brackets, the end portions of said frame each having a plurality of hook receiving sockets, whereby the lower end of said back 105 rest may be supported in different planes.

4. A couch hammock comprising a seat, two upturned ends, hammock suspension means connected therewith, a back, means for connecting the back to both of said ends 110 at a fixed height above the seat and serving as a pivotal support for the effective portion of said back and other adjustable means independent of said upturned ends and coöperating with the lower part of the effective 115 portion of said back to vary the angularity thereof.

In testimony whereof, I have signed my name to this specification, in the presence of two subscribing witnesses.

ISAAC E. PALMER.
